HAIR CURLER

Abraham Goodman, Brooklyn, N. Y., assignor to
Delamere Company, Inc., a corporation of Dela-
ware

Application March 27, 1937, Serial No. 133,359

6 Claims. (Cl. 132—41)

This invention relates to certain improvements in a hair curler of the type having a hair rolling element and a hair retaining clamp swingably and revolvably mounted thereon.

5 An object of the invention is to provide a curler having a hair rolling element that has a handle portion extending rearwardly beyond the mounting of the revolvable clamp, by which handle the curler may be bodily rotated independently of the clamp to wind the curl tightly to the scalp.

Another object is to provide a curler of this type having novel means for revolvably and swingably mounting the clamp on the hair rolling element.

A further object is to provide such a device with means for gripping the ends of the hair on the rolling element preliminary to the rolling operation, which means are protected against 20 accidental catching of hair therein.

One embodiment of the invention is illustrated in the accompanying drawing, in which:

Figure 1 is a side elevation of the hair curler; Fig. 2 is a top plan view thereof;

25 Fig. 3 is an enlarged sectional view taken on the line 3—3 of Fig. 2;

Fig. 4 is an enlarged sectional view taken on the line 4—4 of Fig. 3; and

Fig. 5 is an enlarged sectional view taken on 30 the line 5—5 of Fig. 3.

The curler has a tubular hair rolling element 10, preferably of tapered form, to which is pivoted, at 11, a jaw 12 for gripping the ends of the hair on the rolling element preliminary to 35 rolling or curling the hair. The jaw has an extension 13, lying substantially in the plane of the jaw but which may have a slight upward bulge, as shown. The extension 13 forms a finger piece for opening the jaw against the action of 40 the spring 14.

The rear end of the element 10 is extended in the form of a cylinder 15 of reduced diameter. This cylindrical portion is slightly eccentric with respect to the longitudinal axis of the hair rolling element 10 but is concentrically disposed with 45 the axis of rotation of the curler as a whole. A shoulder 16 is formed on the element 10 adjacent to the portion 15.

A collar, indicated generally by the reference 50 numeral 17, is mounted to rotate freely on the cylinder 15. This collar may be of any suitable construction. In the particular embodiment illustrated, the collar comprises an assembly of two annular disks 18 and 19 spaced apart and having 55 peripheral flanges 20 and 21 that fit over each

other. The flange 20 of disk 18 preferably extends slightly over the rear end of the finger piece 13 of jaw 12 to prevent admission or catching of hair between the parts.

A swingable clamp 22 is pivoted or hinged to 5 the collar 17 at diametrically opposite points. As shown, this clamp may be in the form of a wire loop or bail carrying a roller 23 that snaps into the open end of element 10 when the clamp is swung down into closed or hair retaining position, and having inturned ends 24 pivoted in aligned openings in the collar flanges.

When the collar 17 is in position, a sleeve 25 is forced with a driving fit over the cylinder 15. The sleeve serves as a handle for rotating the 15 curler, and for this purpose it may conveniently have a fluted or knurled surface, as shown. The sleeve has an annular flange 26, which flange, together with the shoulder 16, forms a channel or race in which the collar assembly is freely revol- 20 able on the cylinder 15.

In using the curler, the finger piece 13 is pressed down to open the jaw 12 against the action of the spring 14 and the ends of the hair are gripped between the jaw and the rolling element 10. The 25 clamp 22 is then swung down to closed position, and while the sides of the clamp are held between the fingers of one hand, the rolling element and the jaw are rotated as a unit by turning the handle 25 with the other hand. By reason of the 30 fact that the collar 17 that carries the clamp 22 is freely revoluble on the rolling element, the hair may be wound in a curl and held tight to the scalp. It will be noted that the handle 25 may be comfortably held in the hand and the 35 device rotated without the necessity of holding the finger piece 13 during such rotation.

It is to be understood that various modifications in the details of construction herein described may be made within the purview of the 40 invention.

I claim:

1. A hair curler comprising a hair rolling element, a hair gripping jaw pivoted thereto, an extension on the hair rolling element projecting 45 rearwardly of the rear end of the jaw, a collar revolvably mounted on the extension of the hair rolling element, a clamp pivoted on the collar to close down on the hair rolling element, and a handle on the extension for rotating the hair 50 rolling element together with the jaw independently of the collar when the clamp is in closed position, said extension arranged eccentrically to the hair rolling element.

2. A hair curler comprising a hair rolling ele- 55

ment, a hair gripping jaw pivoted thereto, an extension on the hair rolling element projecting rearwardly of the rear end of the jaw, a collar revolvably mounted on the extension of the hair rolling element, a clamp pivoted on the collar to close down on the hair rolling element, a rim on the collar overhanging the rear end of the jaw, and a handle on the extension for rotating the hair rolling element together with the jaw independently of the collar when the clamp is in closed position.

3. A hair curler comprising a hair rolling element, a hair gripping jaw pivoted thereto, an extension on the hair rolling element projecting rearwardly of the rear end of the jaw, said extension arranged eccentrically to the hair rolling element, a shoulder on the hair rolling element adjacent the extension, a handle fixed to the extension for rotating the hair rolling element, a flange on the handle spaced from the shoulder, a collar revolvably mounted on the extension between the shoulder and the flange, and a clamp pivotally secured to the revolvable collar.

4. A hair curler comprising a rolling element, a jaw pivoted to the rolling element, a finger piece on the jaw for operating the same, an extension of the rolling element rearward of the finger piece, said extension arranged eccentrically to the hair rolling element, a collar freely revolvable

on the extension, a clamp swingably secured to the collar and revoluble therewith, and a handle on the extension disposed to the rear of the collar for rotating both the rolling element and the jaw independently of the collar when the clamp is swung into closed position.

5. A hair curler comprising a rolling element having a cylindrical extension at its rear end, said extension arranged eccentrically to the hair rolling element, a collar freely revolvable on the extension, a clamp hinged to the collar, a hair gripping jaw pivoted to the rolling element at a point in front of the collar, and a sleeve fixed to the extension to the rear of the collar and forming a handle for rotating the rolling element together with the jaw.

6. A hair curler comprising a hair rolling element, a hair gripping jaw pivoted thereto, a finger piece for the jaw extending rearwardly of the pivot, an extension on the hair rolling element projecting rearwardly of the rear end of the finger piece, a collar revolvably mounted on the extension of the hair rolling element, said collar having a rim, said rim overhanging the rear end of the finger piece whereby a guard is formed to prevent catching of stray hair when the curler is in use.

ABRAHAM GOODMAN.
